UNITED STATES PATENT OFFICE.

HENRY F. SCHMIDT, OF PHILADELPHIA, PENNSYLVANIA, ASSIGNOR TO WESTINGHOUSE ELECTRIC AND MANUFACTURING COMPANY, A CORPORATION OF PENNSYLVANIA.

GOVERNOR.

Application filed November 29, 1922. Serial No. 604,033.

To all whom it may concern:

Be it known that I, HENRY F. SCHMIDT, a citizen of the United States, and a resident of Philadelphia, in the county of Philadelphia and State of Pennsylvania, have invented a new and useful Improvement in Governors, of which the following is a specification.

My invention relates to pressure-responsive governors, more particularly to those of the dynamic pressure type, and it has for its object to provide apparatus of the character designated which shall be highly sensitive to load conditions, which shall be simple in construction, which shall be economical and adaptable in its spacial requirements, and which shall be suitable for use with high-power apparatus.

More particularly, my invention has for its object to provide two spring means for loading a pressure responsive element, one of the spring means being of the floating type, that is, it is under substantially constant tension for a given adjustment and moves to different positions corresponding to the positions occupied by the pressure responsive device, the other spring means having one end fixed so that it constitutes a scale spring or loads the pressure responsive element in accordance with its position, in other words, in accordance with the elongation of the latter spring means.

A further object of my invention is to provide means whereby the tension of the load spring may be adjusted to adapt the apparatus for governing at different speeds and while it is in service.

A still further object of my invention is to provide a fluid pressure governor which is suitable for operating large engine or turbine valves without employing fluid or other relay mechanism between the governing mechanism and the part operated or controlled thereby.

Apparatus embodying features of my invention is illustrated in the accompanying drawings, forming a part of this application, in which Fig. 1 is a diagrammatic view of mechanism showing my improved governing apparatus applied thereto; Fig. 2 is a sectional view of my improved pressure-responsive governing device; and Fig.

3 is a sectional view taken along the line III—III of Fig. 2.

It has been proposed to employ a pressure-actuated governing system in connection with machinery such, for example, as steam turbines. Such a system has employed a pump of the dynamic type which develops pressure in accordance with the square of the speed and a pressure-responsive device for actuating the energy-controlling means or admission valve. Ordinarily with large turbines, a relay is employed so that forces other than those developed by the governor serve to move the heavy valve parts and actuating mechanism.

My invention relates to apparatus of this character and more particularly to a pressure-responsive device which is capable of giving sensitive results without the employment of an intermediate relay. The simplest form of pressure-responsive device is an abutment or piston subject to fluid pressure on one side and to spring pressure on the other side; however, with high fluid pressures, the spring becomes inordinately long and impractical in order that sufficient pressure may be imposed and, at the same time, a sufficient range of movement permitted. Accordingly, it is the object of my invention to provide apparatus which will give the requisite spring pressure and permit the use of relatively short spring means and which will, at the same time, afford ample range of controlling movement. More particularly, my invention comprises a pressure-responsive valve connected to an operating piston by a strong or load spring

which is normally under tension to resist the major portion of the fluid pressure, the valve being connected to a stationary element by a weaker spring which assists the strong spring in opposing the fluid pressure. Changes in fluid pressure are taken care of by adjustment of the operating piston and of the piston valve such that the weaker spring is elongated more or less to compensate for pressure changes, the tension of the strong spring being substantially constant for different regulated speed positions for a given speed. The speed may be changed by adjusting the tension of the strong or load spring.

In Fig. 1, I show a rotary mechanism, at 10, for example, an elastic-fluid turbine, which is provided with controllable energy supply means 11, for example, an admission valve, whose position is determined by a motor device, at 12, which acts in response to the pressure of fluid developed by a pump 13, or other suitable means, driven by the shaft or rotary element 14 of the mechanism 10. Fluid is supplied by the pump to the motor device, at 12, by means of a conduit 17 and fluid which is exhausted or leaks off from the motor device is returned by a conduit 18, which communicates with a storage receptacle 19, and the latter is connected to the inlet of the pump, so as to constitute in effect a closed fluid circulating system. The pump, or equivalent means, should be of the dynamic or pressure type, as it should develop a fluid pressure which varies approximately as the square of the speed of the rotary element 14; and, as the fluid pressure varies, the motor device, at 12, acts upon the energy-controlling means 11 to govern the speed of the rotary mechanism.

The structure of the motor device will be clear from a consideration of Figs. 2 and 3. Oil under pressure is supplied to the motor device 12 and it passes up through 30 the hollow piston valve 21, which is closed at its upper end by any suitable means, for example, by a cap 22, for action upon the piston valve in a manner to be described. The hollow piston valve 21 has a close fit 35 with respect to the interior surface of a hollow operating piston structure 24, which is provided with an intermediate operating piston portion 25 and with upper and lower hollow piston-rod portions 26 and 27, the latter portions having a close fit with the flanges 28 and 29, respectively, constituting cylinder heads for the cylinder 30 within which is located the operating piston portion 25. The upper hollow piston-rod portion 26 is connected by any suitable means, for example, the link 32 and the lever 33, to the rod 34 of the admission valve 11.

The piston valve 21 is provided with upper and lower ports 35 and 36, which are 50 adapted to communicate with the ports 37 and 38, respectively, in the piston portion 25, the latter ports leading, respectively, to the upper and lower faces 39 and 40 of said piston portion 25. The piston valve 21 is provided with upper and lower portions 55 41 and 42, which, when the parts are in a cut-off position, as indicated in Fig. 2, cover the ports 37 and 38, respectively, substantially without any lap.

As shown in Fig. 2, the ports 35 and 60 36 are arranged respectively above and below the upper and lower piston ports 37 and 38; and, in order that an accurate relation may be secured between the piston 65 valve and the piston ports, the ports 35 and

36 terminate exteriorly in enlarged recesses or grooves 43 and 44, which define the outer limits of the cut-off portions 41 and 42, respectively, which fit over the recesses 37 and 38 with no lap when the piston valve 70 21 and the operating piston 25 are in a neutral or cut-off position.

Between the cut-off portions 41 and 42, the piston valve 21 is provided with a portion 46 of lesser diameter than the hollow 75 interior of the operating piston so as to define the inner limits of said cut-off portions 41 and 42 and to afford communication between the ports 37 or 38 and the ports 47 of the operating piston portion 25 80 leading to the exhaust space 48, which communicates with the exhaust outlet 49 connected by a conduit 50 to the exhaust line 18. Therefore, when fluid under pressure is admitted to act upon one of the piston faces 39 or 40 the fluid in contact with the other piston face is exhausted through its corresponding port, the space between the reduced portion 46 and the hollow interior 85 of the operating piston 25, the ports 47, the space 48, the port 49, and the conduit 50 to the exhaust line 18.

The upper portion of the piston valve is 90 preferably of a reduced diameter, as at 51, so as to allow the fluid which leaks by to readily flow out through the off-take ports 52 in the piston portion 26, the off-take chamber 53, the off-take port 54, and the conduit 55 to the exhaust line 18.

The piston valve 21 is connected to the lower end of the operating piston rod portion 27 by means of a strong or load spring 57 of the floating type, which serves to bias the piston valve 21 downwardly with respect to the operating piston 25. This spring is preferably connected to the upper end of the piston valve 21 by means of a bolt 58, which is accessible by removal of the cap 22, and the bolt is provided with a nut 59 fitting within the upper convolutions of the spring 57 to securely connect the spring to the piston valve. The lower end of the spring 57 is connected to the lower hollow operating piston portion 27 by means of an adjustable connection so 110 that the tension of the spring may be adjusted in the manner and for purposes hereinafter set forth.

The tension-adjusting and securing means for the lower end of the spring 57 comprises a threaded member 62 securely fitted within the lower convolutions thereof, and the threaded member is connected to an exteriorly threaded sleeve 63 having a spline connection, at 64, with respect to a collar 120 65 secured to the operating piston rod portion 27. An interiorly threaded sleeve 66 engages with the exteriorly threaded sleeve 63 and it has, at its upper end, a swivel connection 67 with respect to the lower end 130

of the operating piston rod portion 27. The exteriorly threaded sleeve 66 has a spline connection, at 68, with respect to an operating worm gear 68' maintained in position by means of a shoulder 69 on the cylinder structure 19 and by a shoulder 70 on the spider 71 secured to the lower end of said cylinder structure. The worm gear 68' is rotated either in one direction or the other by means of a worm 72 secured to a shaft 73, which is provided with an operating hand wheel 74.

The tension of the spring 57 may, therefore, be varied merely by operating the hand wheel 74 in one direction or the other. The operation of the hand wheel results in rotation of the worm gear 68', rotation of the exteriorly threaded sleeve 66, due to the spline connection at 68, and relative longitudinal movement between the exteriorly threaded sleeve 63 and the interiorly threaded sleeve 66, due to the fact that the former sleeve does not rotate because of having the spline connection 64 with respect to the ring 65 secured to the hollow operating portion 27. The swivel connection 67 of the interiorly threaded sleeve 66 with respect to the lower hollow operating piston portion 27 permits of said sleeve being carried by the operating piston to its different positions and the splined connection 68 of the sleeve with the gear 68', permits of relative movement of the sleeve with respect to the gear so that the sleeve may be rotated for different operative positions of the operating piston.

The upper end of the hollow piston valve 21 is also connected to a suitable stationary element 75, carried by the spider 71, by means of a spring 76 which serves to bias the piston valve downwardly with respect to the stationary element 75. The spring 76 is relatively weaker than the spring 57 and constitutes the scale or governing spring of my apparatus.

In operation, the dynamic pump 13 develops pressure of fluid which varies as a function of the speed of the rotating element 14. The fluid under pressure enters the operating cylinder structure 19 by means of the conduit 17 and it passes through the spider and up through the piston valve and operating piston structure to act upon the closed end 22 of the piston valve as well as upon the exposed lower piston surface of the piston valve. In other words, the fluid under pressure is effective against a piston area which has for its diameter the greatest exterior diameter of the piston valve 21.

The pressure of fluid acting upon the piston valve 21 is opposed both by the tension of the load spring 57 and by the tension of the governing or scale spring 76. Under normal operating conditions, the major portion of the fluid pressure is resisted by the

tension of the spring 57, the spring 76 serving to offer a variable resistance depending upon the position of the piston valve 21 and the operating piston 25 as the speed changes and the pressure of fluid varies.

70

Assuming that the parts are in the position as shown in Fig. 2, with the spring 57 under tension and offering the major portion of the reaction which opposes the pressure of fluid, the reaction offered by the spring 76 being dependent upon the position of the piston valve 21, then upon an increase in fluid pressure, due to an increase in speed of the rotating element, for example, upon a decrease in load thereof, the hollow piston valve 21 immediately moves upwardly; and, just as soon as this upward movement commences, the ports 36 afford communication with the ports 38 to supply fluid under pressure to the lower face 40 of the operating piston 25 so as to cause the latter to move upwardly with and relatively to the hollow piston valve 21, and the space above the face 39 is placed in communication with the exhaust by way of passages 37, reduced portion 46, ports 47, and the reduced portion 48.

80

The initial movement of the hollow piston valve 21 results in the springs 57 and 76 being elongated to the same extent; but, as the spring 57 is much stronger, it will bear the greater portion of the increase in load. As soon as the operating piston 25 begins to move, due to the supply of fluid under pressure to the lower face 40 and to the exhaust of fluid from the upper face 39, the increase in tension on the strong or floating spring 57 begins to be transferred to the small spring 76; and the hollow piston valve and the operating piston move together under the influence of fluid pressure until the latter is balanced by the normal tension of the floating spring 57 and the increase in tension on the spring 76 which is brought about by said upward movement, as the lower end of the spring is secured to a stationary element.

95

As the operating piston 25, therefore, follows the piston valve 21, such parts move until the increase in pressure of the fluid is compensated for by elongation of the governing or scale spring 76; and, when this condition is reached, the operating piston 25 and the hollow piston valve 21 move relatively so that the parts are in the position indicated in Fig. 2, with the ports 37 and 38 cut-off by the portions 41 and 42, respectively, of the hollow piston valve.

105

A decrease in pressure in the fluid delivered to the operating cylinder structure, resulting from a decreased speed of the rotary mechanism and, therefore, to an overload, results in downward movement of the hollow piston valve 21 so as to afford communication between the ports 35 and 37 to supply oil under pressure to the piston face

115

120

130

39 and communication of the ports 38 with the exhaust ports 47 by means of the reduced portion 46. The piston valve 21 moves downwardly due to the pressure exerted by 5 the springs being superior to the oil pressure. The piston valve 21 and the operating piston 25 then move downwardly and relatively to each other until the large or floating spring 57 is again substantially under its normal tension and the spring 76 10 has been sufficiently shortened or reduced in tension to take care of the decrease in fluid pressure.

It will, therefore, be seen that the large 15 scale floating spring 57 exerts substantially a constant resistance to the fluid under pressure, this substantially constant tension being maintained due to the fact that the operating piston is capable of following and 20 moving relatively to the hollow piston valve 21; and, as the piston valve 21 and the operating piston 25 are capable of occupying varying elevations, the spring 76 will be elongated in a variable manner to take care 25 of fluctuations in fluid pressure brought about by load variations on the machine.

With the large floating spring 57 under tension, it will be seen that such tension is resisted by the body of fluid in the operating cylinder particularly above the piston face 39. Therefore, with the parts in a neutral or cut-off position as shown in Fig. 2, 30 it is necessary that the portion 41 shall have such a dimension with respect to the port 37 as to permit a slight leakage of fluid under pressure in order to make up for such leakage as takes place above the operating piston face 39.

The governing mechanism may be adjusted 40 to maintain different speeds merely by varying the tension of the large scale spring 57 which may be readily done while the machine is in operation merely by turning the hand wheel 74. Operation of the hand wheel 45 results either in increased or diminished tension of the large scale spring 57 so as to vary the value of the load pressure to be maintained. As the piston valve 21 comes to a neutral or cut-off position when the 50 spring and fluid pressures are in equilibrium, it will be obvious that upon variation in the tension of the load spring 57 a corresponding variation of the fluid pressure is required to bring about an equilibrium condition, and, as the fluid pressure required varies, of course, the speed of the governed mechanism varies.

The operation of the pressure-operated 60 governing mechanism will be more clearly understood from the following example. Assume that the total oil pressure acting on the piston valve 21 is 928 pounds, that 776 pounds is opposed by tension of the load spring 57 and that 152 pounds is opposed 65 by the tension of the governing or scale

spring 76. Also, assume that the scale of the spring 57 is approximately 8 times that of the spring 76. Under these conditions, if the pressure of fluid should increase, say 32 pounds, for equal initial elongations of the 70 springs 57 and 76, the spring 57 will bear 8 times as much load as the spring 76, in other words, for a pressure increase of 32 pounds the large spring may be increased to an extent of 28 pounds and the small spring to an 75 extent of 4 pounds. As soon as the operating piston is capable of moving, it will move until the tension upon the large spring is relieved to the extent of this increase, and when this takes place the piston valve and 80 the operating piston are in a neutral cut-off position but they occupy such a position as to cause such elongation of the small spring 76 as to take care of the additional pressure of 32 pounds. It will, therefore, be seen 85 that the small spring 76 acts as a scale for varying pressures and that the large spring 57 acts to impose an approximately constant load, for a given setting, for all positions.

Downward movement of the operating piston structure, in response to a decrease in fluid pressure, results in downward movement of the link 32 and upward movement of the rod 34 to open the admission valve 11 wider so as to supply more motive fluid to 90 the motor, at 10, in order to take care of the increased load which caused the diminished fluid pressure. On the other hand, if the operating piston 25 is moved upwardly due to an increase in oil pressure resulting from 95 a lightening in load on the machine 10, said operating piston 25 acts through the link 32 and the lever 33 to move the admission valve 11 toward its closing position to restrict the 100 flow of motive fluid to the motor, at 10. If 105 the spring 57 is adjusted so as to respond to low fluid pressures, it is obvious that the motor, at 10, may be governed by the apparatus to operate at a low range of speed. As the tension of the spring 57 is increased, 110 the motor speed is also increased to the extent of developing fluid under pressure which will counterbalance the tension of the springs.

From the foregoing, it will be apparent 115 that I have devised a simple and sensitive speed-responsive, fluid-operated governor in which fluid pressure is opposed by spring means which may be made reasonably short with the capability of resisting high pressures and with the preservation of adequate 120 governor movement to secure a fine adjustment of the admission valve to take care of varying loads. It will also be obvious that operating forces of sufficient magnitude and duration are involved to obtain the requisite movement of the admission valve without the employment of the usual relay mechanism for this purpose.

While I have shown my invention in but 130

one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

10. What I claim is:

1. In a fluid-pressure operated mechanism, the combination of a fluid-pressure operated element, a controlling element for the operated element and movable in response to a variation in fluid pressure, biasing means movable with the controlling element and opposing the fluid pressure imposed on the controlling element, and other biasing means effective in the same direction as the first biasing means and connected to the controlling element and to a stationary element.

2. In a pressure-responsive governor, the combination of an element movable in response to fluid pressure, means for controlling the admission and exhaust of fluid under pressure to said element and subject to fluid pressure in one direction, means movable with the controlling means for opposing the force of fluid pressure applied thereto, and other means for imposing a force on the controlling means in opposition to the fluid pressure force which varies in accordance with the position of the controlling means.

3. The combination with a motor having an admission valve, of governing mechanism for controlling the position of the admission valve comprising means for developing pressure of fluid driven by the motor, means actuated by the fluid under pressure for moving the admission valve, controlling means for admitting and exhausting fluid to the actuated means and movable in one direction by the fluid under pressure, biasing means movable with the controlling means for exerting pressure thereon in the other direction, and means for exerting pressure on the controlling means in said other direction in accordance with position of said controlling means.

4. In a fluid-pressure operated mechanism, the combination of an operated element, a controlling element for the operated element and movable in response to a variation in fluid pressure, a floating spring for connecting the elements and whose tension opposes the fluid pressure, and a spring for connecting the controlling element to a stationary element and opposing the fluid pressure.

5. In a pressure-responsive governor for controlling rotating machinery, the combination of an operating piston, moved by fluid under pressure, a valve for the piston

which is movable in one direction by fluid under pressure, a floating load spring for connecting the valve and piston and opposing the fluid-pressure on the valve, and a scale or governing spring connected to the valve, opposing the fluid pressure applied thereto, and fixed at one end.

6. In a pressure-responsive governor for controlling rotating machinery, the combination of an operating piston, a valve for the piston, a floating load spring for connecting the piston and valve, means for adjusting the tension of the load spring, and a scale or governing spring connected to the valve at one end and fixed at the other end.

7. In combination in a fluid-pressure governor for a fluid motor having a motive fluid admission valve, an operating piston connected to the admission valve and a piston for controlling the admission of pressure fluid to the operating piston, the operating piston and the piston valve being movable to different positions as determined by the speed of the fluid motor, means for exerting a substantially constant pressure on the piston valve in opposition to the fluid pressure for different load positions thereof, and means for exerting additional pressure on the piston valve in opposition to the fluid pressure which varies with the position of the piston valve.

8. In a pressure-actuated governor, an operating piston, a piston valve for admitting fluid under pressure to the operating piston upon relative movement of the valve with respect to the piston and the admission of fluid under pressure being cut off by a relative movement of the operating piston with respect to the valve, biasing means arranged between the piston valve and the operating piston and exerting a substantially constant force on the fluid except when the piston valve moves relatively to the operating piston, and biasing means arranged between the piston valve and a stationary element which assists the first biasing means in opposing the fluid pressure and which serves substantially to absorb the change in pressure taking place in the first biasing means when the piston valve moves relatively to the operating piston so that the force of said first biasing means is maintained substantially constant when the piston valve and the operating piston are in a neutral or cut-off position.

9. In a pressure-actuated governor, the combination of an operating piston, a piston valve for admitting fluid under pressure to the operating piston upon relative movement of the valve with respect thereto in order to secure movement of the operating piston and the admission of fluid under pressure being cut off by relative movement of the operating piston with respect to the piston valve, the piston valve being sub-

jected on one side to the fluid under pressure, and biasing means associated with the piston valve for opposing the fluid pressure.

10. In a fluid-pressure governor, the combination of a cylinder, an operating piston in the cylinder, a piston valve for the operating piston and moved in one direction by fluid under pressure, a spring connecting the operating piston and the piston valve and opposing the pressure of the fluid applied to the valve, and a weaker spring for connecting the valve with a stationary element and also opposing the pressure of fluid applied to the valve.

15. 11. In a fluid-pressure governor, the combination of a cylinder, an operating piston therein having a valve actuating connection at one end, a piston valve, and springs connected to the piston valve and normally under tension in opposition to fluid under pressure admitted to said cylinder, one of the springs being connected to the operating piston and the other to a stationary element.

20. 12. A pressure-responsive mechanism comprising a pressure-responsive element, a pair of springs for loading the element against pressure, a following element to which one of the springs is connected, and a stationary element to which the other spring is connected, whereby, upon a change in pressure, the first element moves to admit fluid under pressure to the second element to move the latter in the same direction, whereupon both elements move until the 25 change in pressure is compensated for by the change in tension of the spring connected to the stationary element.

30. 13. In a fluid-pressure governor for a rotating element, the combination of energy-controlling means for the rotating element, a pressure-responsive valve, a movable abutment connected to said energy-controlling means and which is actuated by fluid under pressure admitted by said valve to follow 35 the motion of said valve, means for loading the valve with respect to the abutment to resist fluid under pressure acting on the valve and serving to secure actuation of the valve when the fluid pressure changes, and other 40 means for loading the valve to balance it against the fluid pressure whose capacity for loading is varied by movement of the abutment to compensate for the change in loading of the first loading means upon initial 45 movement of the valve to maintain the latter loading means at a substantially constant value for different operating positions of the governor.

50. 14. The combination with a machine 55 whose speed is to be governed, having energy-controlling means, and means for developing pressure of fluid in accordance with a function of the speed of the machine, of a pressure-actuated governor comprising 60 an operating element connected to said

energy-controlling means, a valve for admitting fluid under pressure upon relative movement of the valve with respect to said operating element, the pressure being cut off by relative movement of the operating element with respect to the valve, means carried by the valve and which is subject to the pressure of the fluid, and means for exerting pressure on the valve which balances the pressure of fluid applied thereto.

15. In combination with a fluid motor having an admission valve and a pump for developing fluid under pressure which varies as a function of the speed of the motor, of a pressure-actuated device which is connected to the admission valve and which is operated by fluid under pressure received from the pump, comprising an operating piston connected to the admission valve, a piston valve for controlling the admission of fluid under pressure to the operating piston and subject to the effect of fluid under pressure in one direction, tension means arranged between the piston valve and the operating piston and exerting its effect on the valve in a direction opposite to that of the fluid pressure, and other tension means arranged between the piston valve and a stationary element and exerting its effect on the valve in the same direction as the first tension means.

16. The combination with a machine to be governed having an energy-controlling element and means for developing pressure of fluid which varies as a function of the speed of the machine, of operating mechanism movable to different positions in response to variations in fluid pressure to govern the energy-controlling means including a fluid-pressure-actuated abutment, a valve for admitting and exhausting fluid to the abutment and subject to the force of the fluid pressure in one direction, means for biasing the valve to a predetermined extent with respect to the abutment to normally oppose to substantially a predetermined extent the pressure of the fluid applied to the valve, and biasing means between the valve and a stationary element for opposing the pressure of fluid applied thereto to an extent determined by the position thereof.

17. The combination with a fluid motor to be governed having an admission valve and means for developing pressure of fluid which varies as the speed of the motor, of pressure-actuated governing mechanism arranged to receive fluid under pressure from the pressure-developing means and to actuate the admission valve in accordance with variations in fluid pressure comprising an operating piston connected to the admission valve, a valve for controlling the admission of fluid under pressure to the operating piston and movable to different po-

- sitions, means for subjecting the valve to fluid pressure, biasing means effective between the operating piston and the valve for opposing movement of the latter in response to fluid pressure, and biasing means arranged between the valve and a stationary element for assisting in opposing movement in response to fluid pressure, and ports in the valve and in the piston so arranged that, upon a change in fluid pressure, the valve first moves to afford communication between the ports, whereupon the piston follows, moves with, and moves relatively to the valve until the ports are cut off.
15. 18. The combination with a fluid motor to be governed having an admission valve and means for developing pressure of fluid which varies as the speed of the motor, of pressure-actuated governing mechanism arranged to receive fluid under pressure from the pressure-developing means and to actuate the admission valve in accordance with variations in fluid pressure comprising an operating piston connected to the admission valve, a valve for controlling the admission of fluid under pressure to the operating piston, means carried by the latter valve being subjected on one side to fluid under pressure, a load spring connecting the operating piston and its valve and normally under tension to oppose the fluid pressure, and a scale or governing spring arranged between the valve and a stationary element to exert additional pressure against the fluid pressure dependent upon its elongation.
19. The combination with a fluid motor to be governed having an admission valve and means for developing pressure of fluid which varies as the speed of the motor, of pressure-actuated governing mechanism arranged to receive fluid under pressure from the pressure-developing means and to actuate the admission valve in accordance with variations in fluid pressure comprising a piston valve for controlling the admission of fluid under pressure to an operating piston connected to the admission valve so as to cause the operating piston to follow the motion of the piston valve and to move relatively thereto to cut off the supply of pressure fluid to the operating piston to obtain a setting of the latter which is dependent upon the pressure of fluid, a spring for connecting the piston valve and the operating piston and being normally under tension so as to exert a pressure which opposes the fluid pressure, and a spring for connecting the piston valve and a stationary element which serves to exert a pressure on the piston valve to oppose the fluid pressure dependent upon the position of the piston valve.
20. The combination with a fluid motor having an admission valve and means for developing pressure of fluid in accordance with the speed of the motor, of a motor device connected to the admission valve and operative in response to changes of fluid pressure to control the position of the admission valve comprising an operating piston having upper and lower faces and ports leading thereto, a piston valve having communication with the pressure fluid and being provided with upper and lower ports normally out of registry with the operating piston ports but adapted to register respectively upon downward or upward movement of the piston valve relatively to the operating piston, a load spring for connecting the operating piston and the piston valve and being normally under tension to oppose the fluid pressure acting on the piston valve, and a governing or scale spring for connecting the piston valve and a stationary element and being adapted to exert tension upon the piston valve which varies with the position of the latter as determined by the load.
21. The combination with a fluid motor having an admission valve and means for developing pressure of fluid in accordance with the speed of the motor, of a motor device connected to the admission valve and operative in response to changes of fluid pressure to control the position of the admission valve comprising an operating piston having upper and lower faces and pressure supply ports leading thereto, a piston valve having communication with the pressure fluid and being provided with upper and lower pressure supply ports normally located above and below said upper and lower ports respectively of the operating piston but adapted to register therewith respectively upon downward or upward movement of the piston valve, a spring for connecting the operating piston and the piston valve so as to exert pressure on the latter opposed to the fluid pressure, and a scale or governing spring to exert additional pressure on the piston valve which varies with the position of the latter as determined by the load.
22. The combination with a fluid motor to be governed having an admission valve and means for developing pressure of fluid which varies as the speed of the motor, of a motor device which is operated by fluid under pressure and which serves to actuate the admission valve comprising a cylinder having a pressure fluid inlet, a hollow operating piston connected to the admission valve, a hollow piston valve telescopedically arranged with respect to the operating piston and closed at the end opposite to said pressure fluid inlet, ports arranged in the piston valve and in the operating piston, a spring for connecting the piston valve and the operating piston, means for adjusting the position of the piston valve relative to the operating piston, and a scale or governing spring to exert additional pressure on the piston valve which varies with the position of the latter as determined by the load.

ing the tension of the spring, and a spring for connecting the piston valve with a stationary element carried by the cylinder.

23. The combination with a fluid motor
5 to be governed having an admission valve and means for developing pressure of fluid which varies with the speed of the motor, of a motor device which is operated by fluid under pressure and which serves to actuate
10 the admission valve, comprising a cylinder having a pressure inlet port, a hollow operating piston fitting in the cylinder and connected to the admission valve, a hollow piston valve telescopically arranged with respect to the operating piston, ports in the piston valve and in the operating piston to register upon movement of the piston valve relatively to the piston to a predetermined extent and to be cut off upon relative movement thereof, a strong scale spring for connecting the piston valve with the operating piston, and a relatively weaker spring for connecting the piston valve with a stationary element.
- 25 24. The combination with an elastic-fluid motor to be governed having an admission

valve and means for developing pressure of fluid which varies as the speed of the motor, of a motor device which is operated by fluid under pressure and which serves to actuate 30 the admission valve comprising a cylinder having a fluid pressure supply port, an operating piston in the cylinder connected to the admission valve, a piston valve having a range of movement which depends 35 upon the pressure of fluid admitted to the cylinder, a spring for connecting the piston valve to the operating piston and serving to normally impose pressure upon the piston valve which is opposed to the pressure imposed thereupon by the fluid under pressure, means for adjusting the tension of said spring, and another spring for connecting the piston valve to a stationary element so as to impose additional pressure in accordance with the position of said valve to oppose the fluid pressure imposed thereupon. 40

In testimony whereof, I have hereunto subscribed my name this 27th day of November, 1922.

HENRY F. SCHMIDT.
